(57) **CLAIM**

The ornamental design for a step with angled brace and free-end for a vehicle side bar, as shown and described.

DESCRIPTION

FIG. 1 is a front elevation view of a step with angled brace and free-end for a vehicle side bar.

FIG. 2 is a top plan view of the step with angled brace and free-end for a vehicle side bar of FIG. 1.

FIG. 3 is a left side elevation view of the step with angled brace and free-end for a vehicle side bar of FIG. 1.

FIG. 4 is a right side elevation view of the step with angled brace and free-end for a vehicle side bar of FIG. 1; and, FIG. 5 is a perspective view of the step with angled brace and free-end for a vehicle side bar of FIG. 1.

The broken lines shown in the drawings indicate environmental structure or boundaries that form no part of the design.
